UNITED STATES PATENT OFFICE.

WILLIAM T. LARIMORE, OF ST. LOUIS, MISSOURI.

SPRING-MOTOR FOR CARS.

SPECIFICATION forming part of Letters Patent No. 253,072, dated January 31, 1882.

Application filed November 25, 1881. (No model.)

To all whom it may concern:

Be it known that I, WILLIAM T. LARIMORE, of St. Louis, in the county of St. Louis and State of Missouri, have invented certain new and useful Improvements in Spring-Motors for Cars, &c., of which the following is a full, clear, and exact description.

This invention relates to mechanism for horse-cars, to assist the horses in starting of the same, and otherwise in the running of the cars—as, for instance, in ascending inclines; and it consists in a spring band or bands arranged to be coiled from the running of the wheels, and to uncoil, and as it uncoils to work upon the wheels, and thus assist in the movement of the car, all substantially as hereinafter described.

In the accompanying plates of drawings, Figures 1 and 2 are side and plan views, respectively, of the body of a horse-car having my invention attached thereto. Fig. 3 is a cross section on line 33, Fig. 1, enlarged; Figs. 4 and 5, detail views, enlarged, in elevation; Fig. 6, a detail elevation, Fig. 7 a detail plan view, and Fig. 8 a detail sectional view, all enlarged.

In the drawings, A represents a horse car body arranged to run upon wheels B, all as ordinarily.

30 The axle a of one pair of wheels is provided with a gear-wheel, C, with which meshes a pinion-wheel, b, carrying a sprocket-wheel, D, arranged to turn as one in suitable bearings of the car-body.

35 E is an endless chain connecting the sprocket-wheel D with another sprocket-wheel, F, on a horizontal shaft, d, turning in suitable bearings on the car-body, and thus the shaft d is driven from the revolution of the car-wheel axle a. This shaft d carries another sprocket-wheel, G, arranged to turn therewith, and to slide lengthwise thereon, the connection between the two being a horizontal spline, f.

H is an endless chain, connecting sliding 45 sprocket-wheel G with another sprocket-wheel, J, arranged to turn loosely upon another shaft, g. This chain H runs lengthwise of the car and intermediate of the two sprocket-wheels G and J. It passes in one length, h, between the grooved rolls K of an upright post, L, and

in its other length, l, between grooved rolls M of an upright post, N. Each post is arranged to be moved vertically in a separate stationary vertical socket, m, and to be lowered against a spring, n, in its respective socket, and the two posts are arranged out of a longitudinal line with each other, and one upon one side and the other upon the other side of a common longitudinal transverse shaft, O, arranged to turn in suitable bearings on the car-body. 55 This transverse shaft carries a loose sprocket-wheel, P, which is provided with a spring-pawl, o, engaging with a ratchet-wheel, p, of the shaft O, and another loose sprocket-wheel, Q, in line with the post N.

R is a sliding clutch collar on shaft O, arranged to clutch with the vertical face of the sprocket-wheel Q, and to be held to such clutch by a spiral spring, q, on the shaft O, having its bearing at one end against collar R and at 70 its other against an adjustable nut, r, of the shaft O. This clutch turns with the shaft O and can slide lengthwise thereon. The sprocket-wheel P is in line with the length h, and the sprocket-wheel Q is in line with the length l of 75 the chain H.

S is a spring-band coiled around the shaft O, and attached at one end thereto and at the other to the car-body.

T is a ratchet-wheel secured on shaft O, and 80 s is a spring-pawl engaging therewith. This pawl is attached to the car-body, and has an arm, t, in position to be struck by an arm, u, of the sliding post L when such post is depressed against its spring.

U is a line leading from the post L under a pulley-wheel, v, and thence over a pulley-wheel, w, of the car-body, to a drum, V, to which it is secured, which drum is arranged to be turned by a crank-handle, x.

W is a line leading to the drum V, similarly to line U, y z being the pulleys therefor. The turning of the crank-handle in one direction pulls the line U in a direction to depress the post L, and in the other direction it pulls the line W in a direction to depress the post N, and in either case it leaves the opposite post free to lift under the action of its spring. The depression of the one post L puts the length h of chain H which passes between its pul- 100

leys into connection with its sprocket-wheel, and places the other length, l , out of connection with its sprocket-wheel. When the length l of the chain H is in connection with its sprocket-wheel Q the spring S is caused by the revolution of the car-axle to be wound up, and when the length h of chain is in connection with the sprocket-wheel P connection is made for such wound spring to operate upon the car-axle by its unwinding, provided the holding-pawl s is released, which is done by the abutment of the arm u of the post L against the arm t of the pawl s , and the consequent release of such pawl from its engagement with its ratchet-wheel T , and then the shaft O is set free to rotate under the action of the spring, and through the connections described the power of the spring is communicated to the car-axle.

In the operation of the car the chain H , when connected, is in constant motion, and when the line of chain h is engaged with the sprocket-wheel P , if the spring catch or pawl s is not released from the ratchet-wheel T , then the sprocket-wheel P will turn on the shaft O , its spring-pawl o slipping over its ratchet-wheel p ; but as the spring-pawl s is released the spring S will then, in its unwinding, turn the sprocket-wheel P through its pawl and ratchet-wheel connection.

To carry out this invention more fully, an endless chain, H , with its sprocket-wheels, can be arranged on each side of the car and in between the same series of springs S , and shafts can be located as the space will permit, which springs can be arranged to operate as above described, each chain and its connection operating independent springs, or in a series, as desired; also, in lieu of winding up the springs S by the turning of the wheels in the running of the cars, they can be wound by independent means, such as a steam-engine or any power located at different points on the line of travel.

By arranging the endless chain H on each side of the car the wheels at each end of the car can be connected so as to operate, thereby increasing the power over the same.

In the use of this invention in descending hills, the momentum can then be used to wind up the spring S , obviating to some extent the use of the brake, thereby utilizing the power that otherwise would have to be used in braking the car.

The clutch R is arranged to slip or pass over its connection with the sprocket-wheel Q , to prevent the breaking of any of the connecting parts should the chain-connections continue to

operate on the shaft after the spring has been fully wound, such slip being regulated by the spring q and screw-nut r .

The sprocket-wheels G and J , being loose on their respective shafts, can move thereon longitudinally, according to the line of direction in which the chain H is operating, the spline f , however, making a positive connection of the sprocket-wheel G with its shaft for the purpose of operating the chain.

As is obvious, this invention is applicable to the running of the cars in lieu of horses or other motive power.

Having thus described my invention, what I claim, and desire to secure by Letters Patent, is—

1. The coil-spring S , endless chain H , running in line with sprocket-wheels G , P , Q , and J , of which two, P Q , are upon a common shaft, O , in combination with the posts L N and their connections for operating the same, and with sprocket-wheels D F and endless chain E , connected to a car-axle, all substantially as described, for the purpose specified.

2. The coil-spring S , endless chain H , running in line with sprocket-wheels G P Q J , of which two, P Q , are upon a common shaft, O , ratchet-wheel T , and pawl s , in combination with the posts L N and their connections for operating the same, and with sprocket-wheels D F and endless chain E , connected to a car-axle, all substantially as described, for the purpose specified.

3. The coil-spring S , endless chain H , running in line with sprocket-wheels G P Q J , of which two, P Q , are upon a common shaft, O , having sliding clutch R , ratchet-wheel T , and pawl s , in combination with the posts L N and their connections for operating the same, and with sprocket-wheels D F and endless chain E , connected to a car-axle, all substantially as described, for the purpose specified.

4. In combination with the coil-spring S , endless chain H , running in line with sprocket-wheels G P Q J , of which two, P Q , are upon a common shaft, O , in combination with the posts L N and their connections for operating the same, the sprocket-wheel G , connected to its shaft by a spline, f , substantially as and for the purpose specified.

In testimony whereof I have hereunto set my hand in the presence of two subscribing witnesses.

W. T. LARIMORE.
